(57) **CLAIM**

The ornamental design for a brake lever, as shown and described.

DESCRIPTION

FIG. 1 is a front elevational view of brake lever showing my new design;

FIG. 2 is a rear elevational view thereof;

FIG. 3 is a left side elevational view thereof;

FIG. 4 is a right side elevational view thereof; and,

FIG. 5 is a front perspective view thereof.

The broken lines illustrate portions of the brake that form no part of the claimed design.

1 Claim, 5 Drawing Sheets

FIG.1

FIG.2

FIG.3

FIG.4

FIG.5
